DOOR LOCK

Conrad R. Vegren, Chicago, Ill., assignor, by
mesne assignments, to The Youngstown Steel
Door Company, Cleveland, Ohio, a corporation
of Ohio

Application December 22, 1934, Serial No. 758,801

18 Claims. (Cl. 292—283)

This invention relates to door locks and more specifically to locks for sliding doors.

It is an object of this invention to provide a lock for sliding doors which shall effect reduction in the number of parts, decrease in weight, reduction in cost and simplification of replacement of parts.

A further object is to provide a lock which may be furnished and applied as a unit to a door or to a relatively stationary member with which the door is associated.

A further object is to provide locks capable of cooperation with existing parts on a relatively stationary member with which the door is associated to lock the door.

Other objects of the invention will become clear as the description thereof proceeds.

In the drawings forming part of this specification:

20 Figure 1 is a fragmentary elevation of the double doors of a railway car to which a lock embodying the instant invention is applied;

Figure 2 is a view similar to Figure 1, showing a modification;

25 Figure 3 is a view similar to Figure 1, showing a lock embodying the instant invention applied to a box car;

Figure 4 is a vertical section taken on line 4—4 of Figure 1;

30 Figure 5 is a vertical section taken on line 5—5 of Figure 1;

Figure 6 is a horizontal section taken on line 6—6 of Figure 1;

35 Figure 7 is a horizontal section taken on line 7—7 of Figure 2; and

Figure 8 is a horizontal section taken on line 8—8 of Figure 3.

Referring first to Figures 1, 4, 5, and 6 of the drawings a lock embodying the instant invention is shown utilized in connection with the double doors of automobile, furniture and the like freight cars. Such doors are utilized in the sides of railway cars in order to permit the loading and unloading of bulky commodities such as

40 automobiles and furniture with increased facility. These doors are denominated main and auxiliary doors, the main door of the drawings being designated by the numeral 10 and the auxiliary door being designated by the numeral 11. The aux-

45 illary door 11 is provided with a post 12 preferably rigidly secured to the front vertical margin of the door as by means of rivets 13. These rivets are utilized as well to secure to the post 12 and the front vertical margin of the door 11

50 a substantially Z-shaped stop member 14 which

cooperates with a flange 15 provided on the post 12 to provide a recess 16 adapted to receive the front vertical margin of the main door 10. It being customary in closing the doors 10 and 11 to first close the auxiliary door 11 it will be apparent that the member 14 secured to the auxiliary door is utilized as a stop to limit the closing movement of the main door.

The doors 10 and 11 are substantially similar in construction in the sense that each comprises 10 a metallic panel 17 preferably provided with spaced horizontal corrugations 18 which may merge into vertical corrugations 19 provided in the panels adjacent the vertical edges of the door.

A locking device embodying the instant invention may be utilized to fasten the main and auxiliary doors together in closed position. The locking device embodies a substantially plate like or base member 20 secured preferably upon 20 the crests of two adjacent horizontal corrugations 18 in any desired manner, rivets 21 being illustrated as used for this purpose. The plate member 20 is provided with a slot 22 opening through a side of the member. The slot 22 provides means whereby the plate member 20 may 25 slidably support a lock member 23.

The lock member 23 is provided preferably at one of its ends with an inturned flange 24. Intermediate its ends the lock member is provided 30 with an abutment 25 and at its opposite end there is provided preferably integrally therewith a lug 26 directed inwardly with respect to the plate member 20. The lug 26 is disposed within the slot 22 provided in the plate member 20 and is provided with an enlarged portion 27 larger than the width of the slot 22 in order to prevent disengagement of the lock member from the plate member upon outward movement of the former. The plate member 20 is reinforced adjacent the slot 22 by means of a wall 28 conforming in contour to the slot 22 and extending inwardly from the plate member into engagement with the panel 17 of the door intermediate the corrugations 18. The side of the 35 plate member through which the slot 22 opens is provided adjacent said slot with respectively downwardly and upwardly extending walls 29 and 30 adapted to be overlapped by the enlarged portion 27 of the lug 26 in order to prevent sliding disengagement of the lock member 23 from the plate member.

The constructions of the plate member and lock member, however, are such that the lug, together with the enlarged portion thereof, may 40

50

55

be disposed within the space defined by the walls 28, 29 and 30 when the lock member is disposed at an angle of ninety degrees to the plate member. The lock member may then be properly assembled with the plate member by swinging the former through an angle of ninety degrees so as to position the lock and plate members as illustrated in Figure 6 of the drawings. It will be apparent that after this assembly is made the lock member will be retained against sliding and swinging disengagement in a plane parallel to the plate member and that when the plate member is fastened to the door the lock member cannot be disengaged from the plate member.

The plate member carries means adapted to support and retain a locking pin 31. The means preferably takes the form of spaced housings 32 and 33 within which the locking pin 31 is adapted to be received. Complete disengagement of the locking pin is prevented by means of a lug 34 formed on the outer face of the pin adjacent the lower edge thereof. The lug 34 in the vertical movement of the pin is adapted to engage the lug 34A of the upper housing 32 and prevent further vertical movement of the pin.

Corresponding sides of the housing members 32 and 33 are inclined as indicated at 35 and 36. The adjacent side of the pin 31 is correspondingly inclined as indicated at 37. Similarly, the abutment member 25 provided on the lock member 23 is inclined, as clearly indicated in Figure 1 of the drawings. By virtue of the inclination of the parts above mentioned it will be apparent that the lock of the instant invention provides for automatic take-up of any play or tolerance which may exist between the main and auxiliary doors, thereby eliminating stresses imposed upon the elements of the locking device due to impact which would otherwise be incident upon these parts by the back-and-forth movement between the main auxiliary doors.

In the closed position of the doors and in the locking position of the locking device the parts of said device and the main and auxiliary doors will be as illustrated in Figures 1, 4 and 6 of the drawings. It will be manifest that in locking position the inturned flange 24 of the lock member 23 has overlapping engagement with the front stop member 14. The pin 31 is received within the housings 32 and 33 and the inclined side of the pin 31 abuts against the abutment 25 provided on the lock member. In this position of the parts of the locking device it will be apparent that the main door 10 cannot move in the direction of its opening travel, that is, toward the right as viewed in Figures 1 and 6. It will also be apparent that in the event that the main and auxiliary doors are not in the abutting relationship shown in Figure 6, that is, in the event that the main door is not fully closed the locking device will act automatically to absorb the tolerance created by the separation of the doors. This will become apparent when it is considered that the main door may move toward the left in order to properly abut the front stop 14 of the auxiliary door. This movement of the main door will carry with it the pin 31 which is mounted upon the plate member 20 secured to the main door so as to effect disengagement of the pin from the abutment 25. Upon the occurrence of this disengagement the pin will, by the action of gravity, be lowered so that the engagement between the pin and the abutment will again be established. By virtue of the formation of the

slot 22 in the plate member 20 relative sliding movement between the plate member and the lock member may occur.

When it is desired to slide the door toward open position the locking device may be released. Such release may be accomplished after a seal (not shown), and which is utilized to connect the pin to the plate member 20 is removed, by moving the pin 31 upwardly to a point above the upper edge of the lock member 23. The latter may then be swung outwardly so as to be disengaged from the front stop 14 after which it may be permitted to swing downwardly and assume the position designated by the dot and dash lines illustrated in Figure 1 of the drawings. The main and auxiliary doors may then be moved to open position.

Provision is made for the protection of the inwardly extending lug 26 against breakage by impact with the closed end of the slot 22 provided in the plate member. To this end the plate member is provided with a rib 38 capable of being engaged by a depending lug 39 on the lock member 23 prior to the engagement between the lug 26 and the closed end of the slot 22.

If desired, means may be provided to insure against movement of the lock member 23 in the closing direction of the door when such movement is imparted to the main door 10 after the main door has been closed. One form of such means, utilized upon the double door construction illustrated in Figures 1 and 6, is illustrated in Figures 2 and 7 of the drawings. There is shown a bracket member 40 fastened by means of rivets 41 to the front vertical margin of the auxiliary door 11. The bracket member 40 may be provided with a pocket 42 within which the inturned flange 43 provided on a lock member 44 may be received. The inturned flange 43 is preferably inclined rearwardly and cooperates with a forwardly inclined flange 45 provided on the bracket member 40 in order to prevent outward movement of the inturned flange. Slight clearance is provided between the inturned flange 43 and a flange 46 formed on the bracket member and defining one margin of the pocket 42 of said member. It will be seen from the structure above described that should the lock member 44 move in the direction of closing travel of the door, together with the lock plate member and the pin, the inturned flange 43 of the lock member will engage the flange 46 of the bracket member 40, thus limiting the movement of the lock member while permitting the continued movement of the door in its closing direction. By means of this engagement and the continued closing movement of the door there will be effected disengagement between the pin 31 and the abutment 25 provided on the lock member 44. Consequently, the pin will again be automatically lowered so as to take up the closing movement of the door and prevent the return thereof to its former position.

In Figures 3 and 8 the instant invention is illustrated embodied in a locking device applicable to railway box cars, that is, to railway cars utilizing a single door upon each side of the car. The car is provided with a front door post 47 to one leg 48 of which is secured a front stop member 49. The front stop member is adapted to be engaged by the front edge of the door 50 to limit the closing movement of the door. To lock the door 50 in its closed position a locking device substantially similar to the locking device hereinabove described and illustrated in Figures

1 and 6 may be utilized. This locking device embodies the plate member 20 provided with a slot 22 through which extends a lug 26 formed on a lock member 51, differing somewhat in its construction from the lock member 23. The lock member 51 is provided with the abutment 25 adapted to cooperate with pin 31 retained upon the plate member 20 by means of housings 32 and 33.

10 The lock member 51 differs essentially from that disclosed in Figures 1 and 6 of the drawings in that the inturned flange 52 thereof, which has overlapping engagement with the front stop member 49, is provided with a flange 53 extending 15 in the direction of opening movement of the door. This flange 53 overlaps the front stop member 49 so as to prevent disengagement between the lock member 51 and the front stop member by an outward movement of the lock 20 member.

In a railway box car, as well, means may be provided in order to insure relative movement between the sliding door and the lock member. Such means is illustrated in Figure 8 of the drawings and takes the form of an angle member 54, one flange 55 of which is riveted to the front door post 47 while the other flange 56 extends outwardly from the car in overlapping relationship with the inturned flange 52 of the lock member when the latter is in its locking position.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A unit locking device comprising a plate member, a lock member carried by said plate member and a locking pin carried by said plate member, said pin being cooperable with said lock member to maintain the latter in locking position, said plate member being provided with an elongated slot opening through a side thereof, said lock member having a lug extending therefrom disposed for sliding movement in said slot, said lug having a head larger than the width of said slot.

50 2. A unit locking device comprising a plate member, a lock member carried by said plate member and a locking pin carried by said plate member, said pin being cooperable with said lock member to maintain the latter in locking position, said plate member being provided with an elongated slot opening through a side thereof, said lock member having a lug extending therefrom disposed for sliding movement in said slot, said lug having a head larger than the width 55 of said slot and means on said plate member cooperating with said head to prevent sliding disengagement of said lock member.

65 3. A unit locking device comprising a plate member, a lock member carried by said plate member and a locking pin carried by said plate member, said pin being cooperable with said lock member to maintain the latter in locking position, said plate member being provided with an elongated slot opening through a side thereof, said lock member having a lug extending therefrom, said lug having a portion larger than the width of said slot, said lug being disposed for 70 sliding movement in said slot by a relatively angular movement between said lock and plate

members and means for preventing sliding disengagement of said lock member.

4. In a railway car having a relatively stationary member, a slidable door and a front stop member for said door secured to said relatively stationary member, in combination, a locking device for said door comprising a plate member secured thereto, a lock member slidably supported by said plate member and a locking pin carried by said plate member, said lock member having an angularly related flange adapted to overlap said front stop member whereby said lock member is prevented from moving in the direction of opening travel of the door, means secured to said relatively stationary member for limiting movement of said lock member in the direction of closing movement of said door, said pin being cooperable with said lock member to maintain said overlap between said flange and said front stop. 20

5. In a railway car having a relatively stationary member, a slidable door and a front stop member for said door secured to said relatively stationary member, in combination, a locking device for said door comprising a plate member secured thereto, a lock member slidably supported by said plate member and a downwardly tapered locking pin carried by said plate member, said lock member having an angularly related flange adapted to abut said front stop member, 30 a lug provided on said lock member, one side of said pin being cooperable with said lug to maintain said abutment to lock said door.

6. In a railway car having a relatively stationary member, a slidable door and a front stop 35 member for said door secured to said relatively stationary member, said front stop member comprising an angular portion spaced from said relatively stationary member, in combination, a locking device for said door comprising a plate member secured thereto, a lock member slidably supported by said plate member and a locking pin carried by said plate member, said lock member having a hook-shaped flange adapted to have hooked engagement with said angular portion of 40 said front stop member, said pin being cooperable with said lock member to maintain said hooked engagement to lock said door.

7. In a railway car having a relatively stationary member, a slidable door and a front stop 50 member for said door secured to said relatively stationary member, in combination, an outwardly directed flange carried by said relatively stationary member, a locking device for said door comprising a base member secured thereto, a lock 55 member slidably supported by said base member and a locking pin carried by said plate member, said lock member having an inwardly directed angularly related flange adapted to have overlapping engagement with said first mentioned 60 flange and means on said lock member cooperable with said pin to establish locking position of said device.

8. In a railway car having a relatively stationary member, a slidable door and a front stop 65 member for said door secured to said relatively stationary member, said stop member having an outwardly extending portion in combination, a locking device for said door comprising a lock member, means for slidably securing said lock member upon said door and a locking pin provided on said door, said lock member having an inwardly extending angularly related flange adapted to abut said front stop member, said pin being 70 75

cooperable with means on said lock member in the operative position of said locking device.

9. In a railway car having a relatively stationary member, a slidable door associated with said relatively stationary member, in combination, an outwardly projecting flange carried by said relatively stationary member, a locking device for said door comprising a lock member, means slidably securing said lock member upon said door and a locking pin provided on said door, said lock member having an inwardly projecting angularly related flange adapted to have overlapping engagement with said first mentioned flange and means on said lock member cooperable with said pin to establish locking position of said device.

10. In a railway car having a relatively stationary member and a slidable door member, in combination, a locking device for said door comprising a base member secured thereto, a lock member slidably supported by said base member and a locking pin carried by said base member, means provided on said lock member, an abutment member for said lock member secured to said relatively stationary member, said lock member engaging said abutment member and said pin engaging said means in the locking position of said device, said pin and said means being constructed and associated whereby said door and pin are capable of movement toward closed position relative to said lock member in the locking position of said device, said pin automatically engaging said means upon completion of said door movement.

11. In a railway car having a relatively stationary member and a slidable door member, in combination, a locking device for said door comprising a base member secured thereto, a lock member slidably supported by said base member and a locking pin carried by said base member, means provided on said lock member, an abutment member for said lock member secured to said relatively stationary member, said lock member engaging said abutment member and said pin engaging said means in the locking position of said device, said lock member being slidably relative to said base member in the locking position of said device.

12. In a railway car having a relatively stationary member and a slidable door member, in combination, a locking device for said door comprising a lock member, means slidably securing said lock member upon said door and a locking pin having downwardly converging sides carried by said means, means provided on said lock member, an abutment for said lock member secured to said relatively stationary member, said lock member engaging said abutment member and one side of said pin engaging said lock member means in the locking position of said device.

13. In a railway car having a relatively stationary member and a slidable door member, in combination, a locking device for said door comprising a lock member, means slidably securing

said lock member upon said door and a locking pin having downwardly converging sides carried by said means, means provided on said lock member, an abutment for said lock member secured to said relatively stationary member, said lock member engaging said abutment member and one side of said pin engaging said lock member means in the locking position of said device, said door being slidable in the direction of closing movement while said device is in locking position, and means secured to said relatively stationary member engageable with said lock member to prevent movement of said lock member in said direction during movement of said door.

14. A unit locking device comprising a plate member, a lock member carried by said plate member and a locking pin carried by said plate member, said pin being cooperable with said lock member to maintain the latter in locking position, said plate member being provided with an elongated slot, said lock member having a lug extending therefrom disposed for sliding movement in said slot, said lug having a head larger than the width of said slot.

15. A unit lock device for sliding doors comprising a base member adapted to be secured to a said door, a lock member secured upon the outside of said base member for relative horizontal sliding movement, a vertically reciprocable locking pin secured upon the outside of said base member, an angular flange on said lock member and a lug extending from said lock member cooperable with said pin for the purpose set forth.

16. A unit lock device for sliding doors comprising a base member adapted to be secured to a said door, a lock member secured upon the outside of said base member for relative horizontal sliding movement, a downwardly tapering vertically reciprocable locking pin secured upon the outside of said base member, an angular flange on said lock member and a lug extending from said lock member cooperable with said pin for the purpose set forth.

17. A unit locking device for sliding doors comprising a base member adapted to be secured to a said door, a lock member carried by said base member for relative horizontal sliding movement, a downwardly tapering vertically reciprocable locking pin carried by said base member, an angular flange on said lock member and a lug extending from said lock member cooperable with said pin for the purpose set forth.

18. A unit locking device for sliding doors comprising a base member adapted to be secured to a said door, a lock member carried by said base member for relative horizontal sliding movement, a downwardly tapering vertically reciprocable locking pin carried by said base member, a flange extending from said lock member at an angle to the plane thereof and a lug extending from said lock member cooperable with said pin for the purpose set forth.

CONRAD R. VEGREN.
